Primary Examiner — Selina Sikder(74) *Attorney, Agent, or Firm* — Kilpatrick Townsend & Stockton LLP(57) **CLAIM**

The ornamental design for a heatsink for LED, as shown and described.

DESCRIPTION

FIG. 1 is a perspective view of an embodiment of a heatsink for a light-emitting diode (LED) showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is a cross-section view thereof taken along line 8-8 in FIG. 6.

The broken lines in the Figures are for illustrative purposes only and form no part of the claimed design.
